UNITED STATES PATENT OFFICE.

SAMUEL F. NEILL, OF BRADFORD, PENNSYLVANIA.

ELECTRIC IGNITING APPARATUS FOR EXPLOSIVE-ENGINES.

SPECIFICATION forming part of Letters Patent No. 694,409, dated March 4, 1902.

Application filed February 28, 1901. Serial No. 48,986. (No model.)

To all whom it may concern:

Be it known that I, SAMUEL F. NEILL, a citizen of the United States, residing at Bradford, in the county of McKean and State of Pennsylvania, have invented certain new and useful Improvements in Electric Igniting Apparatus for Explosive-Engines; and I do hereby declare the following to be a full, clear, and exact description of the invention, such as will enable others skilled in the art to which it appertains to make and use the same.

My invention relates to improvements in electric firing apparatus for explosive-engines, and consists in the novel features of construction hereinafter described, reference being had to the accompanying drawings, which illustrate one form in which I have contemplated embodying my invention, and said invention is fully disclosed in the following description and claims.

Referring to the drawings, Figure 1 is a side elevation of the magneto-machine, the timing-plate, the spark-coil, and the igniter. Fig. 2 is an end view of the magneto, showing diagrammatically the winding of the field-coils. Fig. 3 is a diagram showing the circuits and the switch, and Fig. 4 is a modification of the form of governor.

In operating explosive-engines it has been difficult to obtain a spark sufficient to ignite the first charge in the cylinder on account of the low speed at which the engine is running at that time in the operation. The armature of the magneto-machine does not cut the field of force of the permanent magnetic poles at sufficient rate of speed to generate the required current. It is the object of this invention to obviate this disadvantage and also to have the spark sufficient at all times to ignite the charge.

Another object of this invention is to construct the circuit-breaker so as to retain the circuit closed through a greater part of the engine's cycle and also to provide means whereby the time of sparking may be changed.

The usual form of magneto employed for furnishing a current for sparking explosive-engines is the form used in this device. A represents the permanent field magnet or magnets of this magneto-machine, and B the armature secured upon the shaft C, which is rotatably mounted on the field-magnet in the

bearings a and carries the centrifugal governor D.

E is a ring loosely mounted upon the movable portion F of the governor D. To this ring E is swiveled one end of the lever G, which is fulcrumed on the arm H, secured to the bearing a' . Upon the free end of the lever G is a brush-switch g , mounted thereon in such a manner that the brush g' will engage the segmental contact-piece I and when operated upon its fulcrum H will engage successively the blocks i , i' , i^2 , i^3 , and i^4 .

Around the two poles of the permanent magnet A are the field-coils J J', which are connected in series with the armature through the brush b by means of the lead b^2 and are wound on said fields in a direction which will increase the magnetism thereof. Between the + brush b and the fields and in the lead b^2 a shunt-wire b^5 is inserted, leading to the segmental contact-piece I, for a purpose hereinafter described. The outleading wire b^4 from the fields is connected to the binding-post l of the primary coil of the spark-coil L.

Upon any suitable shaft M of the engine is mounted the make-and-break contact-cam N. The cam is constructed so that it retains the circuit closed through a greater part of the revolution of the shaft M. This is brought about by making a short break m in the periphery of said cam. Loosely mounted upon the same shaft with said cam is an adjustable plate O, provided with a concentric slot o . A wing-headed bolt o' passes through the slot o and engages a screw-threaded opening in the framework. This slot and wing-headed bolt will serve as a means of adjusting said plate around the shaft, and thus change the time of the spark.

Mounted upon the plate O and secured to the binding-post o^4 is a spring-arm o^2 , provided with a foot o^3 , which normally bears upon the periphery of said cam N. A binding-post p is also mounted on said plate and carries an adjustable contact-point p' . This point p' is in the form of a screw and bears directly against the spring-arm o^2 , thus creating a tension on the same. The binding-post p is electrically connected with the outleading binding-post l' of the primary coil of the spark-coil L. The other binding-post o^4 is connected by the wire o^5 with the - brush b' .

of the magneto-machine. The two wires b^2 and b^3 connect the secondary coil of the spark-coil L with an igniter—in this instance a jump spark-igniter X, which is arranged in 5 the engine-cylinder.

Wound on the poles of the field-magnet A are additional coils, four being shown in the drawings, j , j' , j^2 , and j^3 . These coils are wound on each pole in a contrary direction 10 to that in which the coils J J' are wound and hence have a tendency to demagnetize the poles when the current passes through them. Referring to the diagram shown in Fig. 3 of the drawings, four demagnetizing-coils j , j' , 15 j^2 , and j^3 are shown and are represented as running in an opposite direction to that of the magnetizing-coil J for the purpose hereinbefore stated. The coil j is connected by the wire k to the block i' , the coil j' with the 20 block i^3 by the wire k' , the coil j^2 with the block i^3 by the wire k^2 , and the coil j^3 with the block i^4 by the wire k^3 . One of these sets of demagnetizing-coils is arranged on each 25 of the poles of the magnet A. The demagnetizing-coils j , j' , j^2 , and j^3 are made up of wire of different resistance, the coil j containing the greatest resistance and decreasing in succession to j^3 .

The device operates as follows: The engine 30 is started and motion is conveyed slowly at first to the armature of the magneto-machine through the pulley S or other means. The rotation of the armature through the field of force of the permanent magnet A causes a 35 current to be generated therein. This current after passing through the commutator is led out through the wire b^3 and through the magnetizing-coils J J', hereinbefore referred to. In passing around the poles of 40 the magnet, and thus reinforcing the magnetism thereof, as before stated, the electromotive force of the magneto-machine is increased to such an extent that a spark can be furnished at low speed of sufficient intensity 45 to ignite the first charge. This spark is substantially equal to the one produced at normal speed without the reinforcing-coils. As the engine attains its normal running speed the electromotive force of the magneto-machine 50 will tend to increase; but the increased speed of the shaft of the armature sets the centrifugal governor D, the lever G, and switch g in operation. The switch as it moves over into the block i' throws into the shunt-circuit hereinbefore described all of the 55 demagnetizing-coils wound on the poles of the field-magnet. The effect of this operation is twofold. First, it lessens the amount of current flowing through the magnetizing-coils, 60 and, secondly, it diminishes the strength of the field-magnets by partially demagnetizing the poles. As higher speed is attained these demagnetizing-coils are successively cut out, as hereinbefore described, by the switch g 65 continuing to move over the blocks i^3 , i^3 , and i^4 in succession until the switch reaches the block i^4 . By this means the resistance in

the shunt is gradually cut out, allowing a greater amount of current to pass through the coil j^3 , which is of such character that it 70 will exactly equalize and neutralize the effect of the magnetizing-coils J J'. The passage of the current through the wire b^4 , the primary coil of the spark-coil, the binding-post p , spring-arm o^2 , binding-post o^4 , and 75 thence back to the — brush of the magneto-machine is retained closed through a greater part of the engine's cycle and is only broken upon the cut-away portion m of the cam N reaching the foot o^3 of the spring-arm o^2 . In 80 keeping the circuit closed and breaking it to create the spark the core of the spark-coil is held magnetized continually, with the exception of the point when the circuit is broken, thus giving a better spark. 85

In Fig. 4 I have shown a construction which I desire to use in connection with the governor and switch shown in Fig. 1. m is a solenoid, and m' the soft-iron core thereof, held in its outward position by means of a spring 90 m^5 . The switch-lever R of the automatic switch instead of being pivoted to a stationary part, as shown in Fig. 1, is pivoted to the movable core m' of the solenoid. The spring m^5 is of such strength that it will hold the 95 core against longitudinal movement when the ordinary amount of current passes through the solenoid. This device is used as an additional safeguard in case of a short circuit in the switch at low speed or in case of a failure of the governor to act when the increase of current through the solenoid causes it to overcome the spring and to operate the lever and switch upon the governor-ring as a fulcrum, the operation of the switch throwing 100 in and out the opposing coils hereinbefore mentioned. 105

The solenoid above described may also be used in place of the governor.

I do not limit myself to the exact construction of parts shown or described.

The danger of the permanent field-magnets A ever losing their magnetism or becoming weakened to an extent which would impair their efficiency is obviated by this device, as the magnets are subject to the action of the series of field-coils J J' at starting and stopping. This device is adapted to be used in connection with electric generators which do not have permanent magnetic fields. It may also be used and applied to engines which have other forms of igniting devices than the one shown and described in this application. 115

What I claim, and desire to secure by Letters Patent, is—

1. In an explosive-engine, the combination with an igniting device, of an electric generator therefor provided with a series of demagnetizing-coils of different resistances and a circuit-controller connected with said coils, substantially as described. 120

2. In an explosive-engine, the combination with an igniting device, of an electric generator therefor, provided with coils for increas-

ing the normal magnetism of the field-magnets and coils for demagnetizing said field-magnets, a circuit-controller for said coils and a governor, operatively connected to said circuit-controller, substantially as described.

3. In an explosive-engine, the combination with an igniting device, of an electric generator therefor, provided with coils for increasing the normal magnetism of the field-magnets, a series of coils for demagnetizing said field-magnets, means for cutting in said magnetizing and demagnetizing coils, and means for successively cutting out said demagnetizing-coils, substantially as described.

15 4. In an explosive-engine, the combination with an igniting device, of an electric generator therefor, provided with coils for increasing the normal magnetism of the field-magnets, a series of coils for demagnetizing said field-magnets, a circuit-controller for cutting in said magnetizing-coils and of said demagnetizing-coils and cutting them out successively, and a governor operated by the engine for actuating said circuit-controller.

25 5. In an explosive-engine, the combination with an igniting device, of an electric generator therefor, provided with coils for increasing the normal magnetism of the field-magnets, and a series of demagnetizing-coils of different resistances and a circuit-controller connected with said coils, substantially as described.

35 6. In an explosive-engine, the combination with an igniting device, of an electric generator therefor provided with coils for increasing the normal magnetism of the field-magnets and a series of demagnetizing-coils of different resistances, a circuit-controller connected with said coils and a governor operated by the speed of the engine, operatively connected with said circuit-controller, substantially as described.

45 7. In an explosive-engine, the combination with an igniting device, of an electric generator therefor provided with a magnetizing-coil for increasing the normal magnetism of the field-magnets and a series of demagnetizing-coils, one of which is constructed to neutralize the magnetizing-coil, a circuit-controller connected with said coils, and a governor for actuating said circuit-controller, substantially as described.

55 8. In an explosive-engine, the combination with an igniting device, of an electric generator therefor provided with a magnetizing-coil for increasing the normal magnetism of the field-magnets, and a series of demagnetizing-coils, of graduated resistances, one of which is constructed to neutralize the magnetizing-coil, a circuit-controller connected with said coils and arranged to cut in separately the magnetizing-coil, and all the demagnetizing-coils and to cut out successively the demagnetizing-coils, and a governor operatively connected with said circuit-controller, substantially as described.

65 9. In an explosive-engine, the combination

with an igniting device, of an electric generator therefor provided with a magnetizing-coil and a series of demagnetizing-coils, a circuit-controller connected with said coils and a governor operated by the engine connected with said circuit-controller and an independent electric governor connected with said circuit-controller, substantially as described.

70

10. In an explosive-engine, the combination with an igniting device, of an electric generator therefor provided with a magnetizing-coil and a series of demagnetizing-coils, a circuit-controller provided with contacts, separately connected to said coils, a movable switch-lever, an electric governor having a movable part pivotally connected to said switch-lever, said pivotal connection forming the normal fulcrum of said lever, and a governor operated by the engine connected with said lever, substantially as described.

75

11. In an explosive-engine, the combination with the igniting device, of an electric generator therefor, provided with auxiliary magnetizing and demagnetizing coils, a circuit-controller for said coils and a governor for operating said circuit-controller, of a cam on a shaft operated by the engine, a plate adjustable around said shaft, an igniter-operating device mounted on said plate and operatively engaging said cam, and connections between said igniter-operating device and the igniting device, substantially as described.

80

12. In an explosive-engine, the combination with an igniting device, of an electric generator therefor provided with an auxiliary magnetizing-coil for increasing the normal magnetism of the field-magnets and a series of demagnetizing-coils, a circuit-controller connected to said coils, a movable switch-lever for said circuit-controller, a governor operated by the engine connected to said switch-lever, a solenoid located in the main circuit of the generator, a movable core therefor and connections between said core and said switch-lever, substantially as described.

85

13. In an explosive-engine, the combination with an igniting device, of an electric generator therefor provided with an auxiliary magnetizing-coil for increasing the normal magnetism of the field-magnets and a series of demagnetizing-coils, a solenoid located in the main circuit of the generator, a movable core therefor, a spring holding said core in one position, a circuit-controller for said coils having a movable switch-lever pivoted to said core, and a governor operated by the engine and operative connections between said governor and said switch-lever located in a different plane from its pivotal connection with said core, substantially as described.

90

In testimony whereof I affix my signature in the presence of two witnesses.

SAMUEL F. NEILL.
